UNITED STATES PATENT OFFICE.

WILLIAM T. HOWES, OF WHITE HEATH, ILLINOIS.

PAINTER'S SCAFFOLD.

SPECIFICATION forming part of Letters Patent No. 323,152, dated July 28, 1885.

Application filed May 29, 1885. (No model.)

To all whom it may concern:

Be it known that I, WILLIAM T. HOWES, of White Heath, in the county of Piatt and State of Illinois, have invented a new and Improved 5 Painter's Scaffold, of which the following is a full, clear, and exact description.

The object of my invention is to provide a new and improved painter's scaffold, which is so constructed that the operator can easily 10 and conveniently raise or lower himself or move to any place on the side of a house to which the device is attached.

The invention consists of a frame having a seat and provided with a pivoted pulley-block, 15 of clamps, pulleys, and ropes, and of levers attached to the pulley-block for fastening the ropes which hold the frame.

The invention also consists of various parts and details hereinafter more fully set forth 20 and described.

Reference is to be had to the accompanying drawings, forming part of this specification, in which similar letters of reference indicate corresponding parts in all the figures.

25 Figure 1 is a front elevation showing my improved painter's scaffold attached to a gable-roofed house. Fig. 2 is a side elevation of the frame and the pivoted pulley-block. Fig. 3 is a plan view of the pulley-block. Fig. 4 is 30 a vertical section of the same on the line $x-x$ of Fig. 3, and Fig. 5 is a bottom view of the pulley-block.

The frame A is of suitable construction, and is provided with the seat B, the foot-rest C, the 35 braces C', which serve as a ladder, and the hooks D, on which the operator can place his paint-buckets, &c.

To the upper part of the frame A is pivoted a block, E, having recesses E', in which are 40 placed the four pulleys F F and F' F'.

To the under side of the pulley-block E is attached a plate, G, having recesses G', in which are placed the notched levers H, fulcrumed in the plate G, and through which recesses G' pass the lower ends of the ropes. 45 The under side of the pulley-block E is also provided with hooks H', in which the levers H can be held in a horizontal position. To the outer edges of the pulley-block E are pivoted the clevises E'', to each of which is attached one end of the ropes I and I', and in

the middle, on the top of the pulley-block E, is pivoted a clevis, E'', to which is secured the pulley J.

The clamps K and K' are provided with the 55 pulley-blocks I² and I', attached pivotally to the same, and the clamps K² K² are united by a ring, K³, to which is attached a pulley-block, K⁴. The said pulley-blocks I², I', and K⁴ carry each a pulley. One end of the rope L is attached to the pulley-block K⁴, and passes down and around the pulley J and up and over the pulley in the pulley-block K⁴, and down through the recess G', between the pulleys F' F', to the ground. 60

The ropes I and I', attached to the clevises E², pass each from there over to and around the pulley in the pulley-blocks I² and I' and back again, and over the pulleys F F, and thence down to the ground. 65

The device is used and operated as follows: The clamps K² are attached to the comb of the house to be painted, and the clamps K and K' are secured to the eaves, one on each side. The operator places himself in the seat B, and 70 the ropes being attached, as before described, the operator is then enabled to raise or lower himself or move to any point on the side of the house to be painted by pulling on the respective ropes I, I', or L. As soon as the operator has reached the desired point he unfastens the levers H, which, with their notched edges, tightly clamp the ropes I, I', and L in the recesses G' of the plate G, and thereby suspend the frame A and its attachments at the 75 place desired. In case the operator cannot conveniently reach a desired spot from the seat B he can go up the braces C' C' and from there reach the desired point. In case the side of a house is to be painted, the clamps K 80 and K' are fastened to each end of the eaves and the clamps K² K² midway between them to the eaves. 85

Having thus described my invention, what I claim as new, and desire to secure by Letters 90 Patent, is—

1. In a painter's scaffold, the frame A and the pivoted pulley-block E, in combination with the ropes I, I', and L, the pulley-blocks I², I', and K⁴, the clamps K, K', and K², and 95 the ring K³, substantially as shown and described.

2. In a painter's scaffold, the frame A, the pivoted pulley-block E, and the levers H, in combination with the ropes I, I', and L, the pulley-block I², I³, and K⁴, the clamps K, K', and K², and the ring K³, substantially as shown and described.
3. In a painter's scaffold, the frame A, the seat B, the foot-rest C, the braces C', and the hooks D, in combination with the pivoted pulley-block E, having the recesses E', the pulleys F and F', the clevises E² and E³, the plate G, having the recesses G', the levers H, and the hooks H', substantially as shown and described.
4. In a painter's scaffold, the frame A, the seat B, the foot-rest C, the braces C', the hooks D, the pivoted pulley-block E, having the recesses E', the pulleys F and F', the clevises E² and E³, the plate G, having the recesses G', the levers H, and the hooks H', in combination with the ropes I, I', and L, the pulley-

blocks I², I³, and K⁴, the pulley J, the clamps K, K', and K², and the ring K³, all operating substantially as shown and described.

5. In a painter's scaffold, the pulley-block 25 E, having the recesses E', the pulleys F and F', the clevises E² and E³, the plate G, having the recesses G', the levers H, and the hooks H', in combination with the ropes I, I', and L, the pulley-blocks I², I³, and K⁴, the pulley J, 30 the clamps K, K', and K², and the ring K³, substantially as shown and described.

6. In a painter's scaffold, the pulley-block E, having the recesses E', the pulleys F and F', the clevises E² and E³, the plate G, having 35 the recesses G', the levers H, and the hooks H', substantially as shown and described.

WILLIAM T. HOWES.
